UNITED STATES PATENT OFFICE.

JOHN TYDINGS, OF PHILADELPHIA, PENNSYLVANIA.

RECEPTACLE-SUPPORTING BRACKET.

Application filed April 27, 1921. Serial No. 465,054.

To all whom it may concern:

Be it known that I, JOHN TYDINGS, a citizen of the United States, residing at Philadelphia, in the county of Philadelphia and 5 State of Pennsylvania, have invented new and useful Improvements in a Receptacle-Supporting Bracket, of which the following is a specification.

My invention relates to new and useful 10 improvements in a receptacle supporting bracket, and has for its object to provide an exceedingly simple and effective device of this character which may be readily and quickly placed upon or removed from a gas fixture or similar object or hung upon a wall by means of a nail or its equivalent to support a receptacle above the flame of a gas burner or lamp whereby the contents of the receptacle will be heated.

20 A further object of the invention is to form such a bracket from wire bent and twisted upon itself to produce an upright, a reach and strut with a socket and oppositely projecting feet at the junction of the upright and strut, a hook of a second socket at the junction of the upright and reach and opposed to the first mentioned socket and an eye at the junction of the reach and strut for the reception of a suitable hanger.

30 A further object of the invention is to provide an adjustable extension in combination with the bracket formed as above stated.

A still further object of the invention is to provide a bracket formed of wire consisting 35 of an upright, a reach and a strut with an eye at each end of the reach and a relatively wide base at the lower end of the upright, such construction of bracket being particularly adapted for hanging upon a wall 40 or other similar object.

With these ends in view, this invention consists in the details of construction and combination of elements hereinafter set forth and then specifically designated by the 45 claims.

In order that those skilled in the art to which this invention appertains, may understand how to make and use the same, I will describe its construction in detail, referring 50 by numerals to the accompanying drawings forming a part of this application, in which:—

Fig. 1, is a side elevation of a receptacle supporting bracket made in accordance with 55 my improvement and showing it applied to a gas light fixture.

Fig. 2, is an end view thereof.

Fig. 3, is a side elevation of the adjustable extension member for use with the bracket.

Fig. 4, is a plan view thereof.

Fig. 5, is a portion of the upper socket being broken away.

Fig. 6, is a similar view of the bracket with the adjustable extension member thereon.

Fig. 7, is a side elevation of a modified 65 form of my invention.

Fig. 8, is an end view thereof.

Fig. 9, is a section of the bracket at substantially the line 9—9 of Fig. 1, showing 70 such bracket used in connection with a wall fixture.

In carrying out my invention as embodied in Figs. 1 and 2, 2 represents the receptacle supporting bracket formed from wire suitably bent and twisted upon itself to form an upright 3 having a socket 4 formed at its lower end open at the rear or away from the upright as plainly shown in Fig. 5 and the ends of the legs 5 forming the socket are bent outward in opposite directions to produce the oppositely disposed feet 6 while at the upper end of the upright is formed a second socket or hook 7 which opens toward or adjacent the upright and therefore is opposed to the socket 4, as plainly shown in Fig. 6 and from the upper end of the upright projects the reach 8 having an eye 9 produced at its outer end, said reach being supported or braced by a strut 10 running from the lower end of the upright 3 to the outer end of said reach. To the eye 9 is connected a suitable hanger 11 preferably in the form of a hook having a coiled eye 12 so that it may be attached to the eye 9 after the manner of the well known key ring.

In practice the socket 4 is brought into registration with the upright portion of a gas fixture 13 and the socket member or hook 7 then caused to engage the upright portion of the gas fixture from the opposite side at which time the hanger 11 will be located some distance above the gas burner 14 so that a receptacle placed upon the hanger 11 will be heated by the flame of the burner 14.

Where it is not desired to use the bracket on a gas fixture but it is desired to use the same in conjunction with a wall gas fixture or a lamp placed in proximity to the wall the socket member or hook 7 may be placed over a nail or an equivalent supporting device and the feet 6 allowed to rest against

the wall which will hold the supporting bracket in the proper position for supporting the receptacle by means of the hanger above a lamp or wall gas fixture and as shown in Fig. 9 when used with wall gas fixture having its supply pipe 26 positioned on the outside of the wall, the socket 4 will register with the supply pipe and permit the feet to rest upon the wall. The feet 10 resting upon the wall will reduce to a minimum the likelihood of the bracket swinging on the axis of its upright 3 while the socket registering with the pipe will prevent a sidewise or pendulum of the bracket from its hook.

From the foregoing it will be seen that I have provided a receptacle supporting bracket which may be utilized with gas fixtures of different styles or which can be 20 used where gas fixtures do not exist, thus making it applicable for farm or country use as well as city use.

In Figs. 3 to 6 I have shown the bracket provided with an adjustable extension member 25 and in this case the eye 9 is preferably set at an angle to the reach so that when the adjustable extension member 15 is in place it will practically coincide with said reach. This adjustable extension member is 30 also made of wire bent and suitably coiled upon itself to form a body 16 having notches or recesses 17 formed therein for registration with a portion of the eye 9 to hold it against accidental displacement after the 35 desired adjustment is obtained. At one end of the body is formed an eye 18 to receive the hanger 11 and at the other end are formed the spaced fingers 19 adapted to straddle the reach 8 as plainly shown in 40 Fig. 6 which prevents the weight on the outer end of the extension member from displacing the inner end of the extension member.

This form of supporting bracket may be 45 used with different gas fixtures having the burners different distances from the upright portion thereof as said extension member can be moved inward until the eye 18 thereof is approximately in the same position as the eye 9 or it may be moved out practically the entire length thereof.

The form of bracket illustrated in Figs. 7 and 8 is particularly adapted for use with wall gas fixtures or with lamps and comprises an upright 20 having a relatively 50 wide coil 21 at its lower end to act as a

base for engagement with a wall or other similar flat surfaced object, while from the upper end is formed an eye 22 from which projects the reach 23 having the eye 24 at 60 its outer end for the reception of the hanger 25, said outer end of the reach being supported by the strut 26 projecting between said reach and the lower end of the upright and all of these parts with the exception of the hanger 25 are formed from a single piece of wire bent and coiled back and forth upon the different strands as will be obvious.

Of course I do not wish to be limited to the exact details of construction as herein shown as these may be varied within the limits of the appended claims without departing from the spirit of my invention.

Having thus fully described my invention, what I claim as new and useful is:—

1. In a device of the character stated, an upright having a socket at its lower end which opens out or away from said upright, feet formed with said socket, a second socket at the upper end of the upright opening inward toward the upright or in opposition to the first mentioned socket, a reach projecting from the upper end of the upright, a strut connecting the lower end of the upright with the outer end of the reach, an eye formed at the junction of the reach and strut and a hanger connected thereto.

2. In a device of the character stated, an upright having a socket at its lower end which opens out or away from said upright, feet formed with said socket, a second socket at the upper end of the upright opening inward toward the upright or in opposition to the first mentioned socket, a reach projecting from the upper end of the upright, a strut connecting the lower end of the upright with the outer end of the reach, an eye formed at the junction of the reach and strut, an adjustable extension member consisting of a body having notches therein, an eye formed at one end of the body, a pair of spaced fingers formed at the opposite end of said body, said extension member passing through the eye at the junction of the reach and strut with the spaced fingers straddling said reach, and a hanger attached to the eye on the body.

In testimony whereof, I have hereunto affixed my signature.

JOHN TYDINGS.
